[57] CLAIM

The ornamental design for a combined book cover and reading lamp, as shown and described.

DESCRIPTION

FIG. 1 is a perspective view of a combined book cover and reading lamp in an opened position showing our new design;

FIG. 2 is a front elevational view thereof;

FIG. 3 is a rear elevational view thereof;

FIG. 4 is a top plan view thereof;

FIG. 5 is a bottom plan view thereof;

FIG. 6 is a right side elevational view thereof, the undisclosed side being the same;

FIG. 7 is a front perspective view thereof with the reading lamp extended; and

FIG. 8 is a rear perspective view thereof.
